UNITED STATES PATENT OFFICE.

BERNATH ROSENFIELD, OF TUCSON, ARIZONA.

CLASP FOR RIBBON-BOLTS.

1,080,999.

Specification of Letters Patent.

Patented Dec. 9, 1913.

Application filed June 26, 1913. Serial No. 775,997.

To all whom it may concern:

Be it known that I, BERNATH ROSENFIELD, of Tucson, in the county of Pima and State of Arizona, have invented certain new and 5 useful Improvements in Clasps for Ribbon-Bolts; and I do hereby declare the following to be a full, clear, and exact description of the invention, such as will enable others skilled in the art to which it appertains to 10 make and use the same.

This invention relates to improvements in holders or clasps for use on bolts of ribbon, the object being to provide a simple device which can be readily and quickly applied to a bolt of ribbon without releasing the free end of latter, for holding the free end of the ribbon in place and at the same time permitting the ribbon and the separating paper to be readily unwound.

20 A further object is to provide a device of the character specified, with improved means for locking the free ends of the two members against the possibility of accidental separation.

25 With these objects in view my invention consists in the details of construction as will be more fully explained and pointed out in the claims.

In the accompanying drawings, Figure 1 30 is a view in perspective showing the application of my improvement to a bolt of ribbon. Fig. 2 is a view in side elevation of the clasp in its closed and locked position. Fig. 3 is an enlarged end view showing the 35 lower member locked. Fig. 4 is a similar view showing the lower member unlocked. Fig. 5 is a similar view showing the free end of the lower member being guided into the keeper formed in the bent end of the upper member, and Fig. 6 is a view of a modified form.

The clamp 1 is made from a narrow strip of spring metal, bent centrally upon itself to form two superimposed parallel members 45 2 and 3, the free ends of which are normally held in contact by the abrupt bend and by the elasticity of the metal. The free end of the upper member is bent downwardly as at 4, and the lower edge 5 of the downwardly bent end is beveled upwardly from one side and is provided immediately adjacent the body of the upper member with a slot 6 partly closed by the shoulder 7 at the open end of the slot. This bent end 4, therefore 50 constitutes the keeper for the free end of the lower member 3.

The lower member 3 is provided at its free end with a tongue 8, which is so located with relation to the keeper 4 on the upper member, as to bear against the inclined face 5 of said keeper and also enter the slot 6 therein, without projecting appreciably beyond said keeper. By this construction, the free end of the lower member is in effect, protected and housed so as to 60 prevent injurious contact of same with other goods which may be in contact with the ribbon bolt.

In constructing the clasp the lower member is bent laterally and put under a tension which carries its free end to the side of the keeper farthest removed from the open slot 6, so that in moving the tongue 8 up the incline and toward the slot, the tension or torsion of the lower member will be increased, so that as soon as the open slot is 70 reached the tongue will fly into the same and be retained therein against accidental displacement.

When the lower member 3 has been passed 75 below several thicknesses of ribbon and separating strip of paper, the ribbon and paper operate to separate the members and force the tongue down into the plane of the shoulder 7 and thus prevent a separation 80 of the parts, even should the friction of the ribbon against the members of the clamp, in unwinding the ribbon from the bolt, be sufficient to overcome the spring action or torsion, which tends to hold the tongue 8 85 away from the open end of slot 6, in the keeper.

For wide bolts, or those over three inches in width, I prefer to provide the clasp with finger pieces 9, which are conveniently 90 formed by bending the upper member into inverted U-shaped projections or folds, preferably located equi-distant from the ends of the clasp, and sufficiently close together to be grasped by a finger and thumb of one 95 hand.

In applying the clasp to a bolt of ribbon, the lower member 3 is passed between the convolutions of the ribbon and separating strip of paper, near the periphery of the bolt, so that several layers of ribbon and paper will be between the members 2 and 3 of the clasp. The application of the clasp to the roll or bolt is facilitated by grasping the finger holds and pressing them toward 100 each other. This bows the upper member and causes the free end of the lower member 105 110

to project below the keeper 4, so as to be readily entered between the convolutions of the ribbon. After the lower member of the clasp has passed through the roll, by simply 5 grasping the free end of the clasp between the finger and thumb, and forcing the lower member laterally into the plane of the upper member, the tongue rides against the inclined edge 5 of the keeper 4 until the 10 slot 6 is reached, and is then drawn into the slot by the torsion of the spring.

The construction shown in Fig. 6 is identical with that shown in Figs. 1 to 5 inclusive, except that it is not provided with the finger 15 holds. This form is intended principally for clasps for narrow ribbon bolts.

Having fully described my invention what I claim as new and desire to secure by Letters-Patent, is:

20 1. A ribbon clasp or holder consisting of a flat metal strip bent upon itself to form two parallel members the upper one of which is provided with a right angle bend adjacent its free end, the said bent end having a slot 25 open at one side and the free edge of said bent end being inclined downwardly from said slot, the lower member provided at its free end with a tongue adapted to rest with-

in the slot, said lower member normally projecting to one side of the upper member 30 so that a pressure is required to force the tongue on the lower member into the slot in the bent end of the upper member.

2. A ribbon clasp or holder consisting of a flat metal strip bent upon itself to form 35 two parallel members, the upper one of which is provided with two inverted U-shaped folds forming finger holds, and also provided with a bent end the latter having an inclined lower face and an open slot at 40 the upper end of the incline, and the lower member provided at its free end with a tongue adapted to rest within said slot, the lower member normally projecting to one 45 side of the upper member so that a pressure is required to force the tongue on the lower member into the slot in the bent end of the upper member.

In testimony whereof, I have signed this 50 specification in the presence of two subscribing witnesses.

BERNATH ROSENFIELD.
